PACKAGE AND METHOD OF FORMING THE
SAME

Douglas M. McBean, Canajoharie, N. Y., assignor
to Beech-Nut Packing Company, Canajoharie,
N. Y., a corporation of New York

Application June 27, 1933, Serial No. 677,819
Renewed July 29, 1936

10 Claims. (Cl. 229—51)

My invention relates to packages that have an outer wrapper of cellulose acetate or similar material, especially small packages of chewing gum, candies and other articles, and further relates to 5 a method of wrapping the packages in such material.

One of the objects of my invention is to provide a novel and improved package of this character, and method of producing the same.

10 Another object of the invention is to provide a novel and improved package of this character in which the cellulose acetate wrapper may be easily and quickly separated into two parts adjacent one end of the package.

15 A still further object of the invention is to provide a method of forming the cellulose acetate wrapper and applying it to the package whereby it may be easily and quickly removed.

The several features of the invention, whereby 20 the above mentioned and other objects may be attained, will be readily understood from the following description and accompanying drawings in which:

Figure 1 is a view in perspective of a package of 25 gum, wrapped in cellulose acetate in accordance with my improved method;

Fig. 2 is a similar view illustrating the manner in which one end portion of the cellulose acetate wrapper may be severed;

30 Fig. 3 is a similar view with the severing strip torn from the cellulose acetate wrapper and with the severed end of the wrapper shown by broken lines removed from the package;

Fig. 4 is a view similar to Fig. 1 of a cylindrical 35 package such as a roll of fruit drops;

Fig. 5 is a plan view, partly diagrammatical, of a strip of cellulose acetate or similar material from which the wrappers may be formed and the devices that may be employed in forming the 40 wrappers;

Fig. 6 is a detail sectional elevation, on an enlarged scale, taken on the line 6—6 of Fig. 5;

Fig. 7 is a view in perspective of one of the cellulose acetate wrappers; and

45 Fig. 8 is a sectional view taken on the line 8—8 of Fig. 7.

In forming the cellulose acetate wrappers in accordance with my improved method, a strip 2 of cellulose acetate may be fed longitudinally as 50 by means of rolls 4 and 5, the grain of the cellulose acetate extending generally longitudinally thereof. The upper one of the rolls 4 is provided with a suitably formed annular projection 6, and

55 the lower roll 4 is provided with an annular groove 8 which receives the projection 6. As the

cellulose acetate passes between the rolls 4, the projection 6 and wall of the groove 8 cooperate to form a straight-sided corrugation 10 in the strip in proximity to one of its longitudinal edges. As the cellulose acetate strip leaves the forming 5 rolls 4, the corrugation 10 is engaged by suitable folding devices 11 which turn over the corrugation on the under side of the strip, and then the folds thus formed are flattened by means of the rolls 5 so as to form a narrow double 10 fold or pleat 12.

As the strip is fed along after passing the pressure rolls 5, slits 14 are made in the strip adjacent and parallel to the pleat 12. After the slits are made pieces of the strip are cut off from 15 the advancing end thereof to form the wrappers 16. Serrated cutters (not shown) are used in thus severing the strip so that the resulting wrappers each have serrated edges 18 and 19. The pieces are cut off through the slits 14 so as to 20 provide slits in the edges 18 and 19 of the wrappers. These slits 14 in at least the edge 18 of the wrapper preferably extend through the inner apexes of two of the serrations, as shown. The cutters also form a substantially U-shaped cut in 25 the cellulose acetate so as to provide the edge 18 with a projecting tab 20. The longitudinal edges of this tab are preferably continuations of the slits 14 in the edge of the wrapper, the pleat 12 extending centrally through the tab. The cutting 30 out of the tab provides the edge 19 of each wrapper with a correspondingly shaped notch 22. It may be noted that the grain of the cellulose acetate in each wrapper extends generally in the same direction as the pleat 12. 35

The cellulose acetate wrapper may be folded about the package either by hand or by means of suitable wrapping mechanism. The wrapper is preferably applied so as to cause the pleat 12 to completely encompass the package. The serrated edge 18 and the tab 20 form the outer edge of the wrapper, and in case of straight sided packages, such as shown in Figure 1, the tab may project beyond one of the longitudinal edges thereof. In case of elongated packages such as 45 shown in the drawings, the pleat 12 may be arranged in proximity to one end of the package as shown. The overlapping edges 18 and 19 of the cellulose acetate wrapper may be secured together by adhesive 24, and if desired the tucked in ends 50 or other folds of the wrapper may be secured together so as to make a substantially air tight package.

With the cellulose acetate wrapper thus formed and applied, to open the package it is merely 55

necessary to grasp the projecting tab 16 with the fingers and then pull the tab about the package. While it is difficult to start a tear in a sheet of cellulose acetate, when a tear is started 5 across one edge, or a cut is initially made therein, the cellulose acetate will readily tear especially if the tear is made in the general direction of the grain of the cellulose acetate. I have found that by making the slits 14, which are 10 continuations of the longitudinal edges of the tab, that the cellulose acetate will tear very readily and that the reinforcing portion of the wrapper provided by the pleat 12 will insure the tears on each side of the pleat continuing as 15 the tab is pulled about the package, so that a strip 28 (Fig. 3) may be easily torn from the cellulose acetate wrapper, thus severing the wrapper in two. I have also found that satisfactory results may be secured without the use of the 20 slits 14 provided the longitudinal edges of the tab extend to the apexes of the serrations in the edge 18 of the strip. It will be obvious also that the tear may be started by any suitable notches or cuts in the edge 18 of the wrapper, and in 25 fact where the outer edge of the wrapper is securely affixed with the tab projecting, the slits or notches or other cuts may be dispensed with. The reinforcing pleat 12 tends to cause the strip to be evenly torn from the package, but in case 30 the torn part should not run evenly and the tear extends to the side of the pleat, it is thereby prevented from extending further in that direction, thus obviating the danger of the strip breaking while being torn from the wrapper.

35 In addition to the pleat providing convenient means for opening the package, it compensates for shrinkage of the cellulose acetate which is likely to cause it to break as it shrinks tightly over the article. As the cellulose acetate shrinks 40 the pleat pulls out slightly, but still remains flat about the package.

The present application is a continuation in part of applicant's co-pending application Serial No. 627,325, filed August 3, 1932.

45 It is to be understood that the term "cellulose acetate" shall be construed to include any transparent sheet material having similar physical characteristics to cellulose acetate.

As will be evident to those skilled in the art, 50 my invention permits various modifications without departing from the spirit thereof or the scope of the appended claims.

What I claim is:

1. In a package of gum or other package having 55 an outer wrapper of cellulose acetate, the improvement which comprises a tab projecting from the outer edge of the cellulose acetate wrapper and a fold in the cellulose acetate wrapper providing a reinforcing strip portion extend-

ing about the package with one end extending through said tab.

2. In a package of gum or other package having 5 an outer wrapper of cellulose acetate, the improvement which comprises a fold in the cellulose acetate wrapper providing a reinforcing strip portion extending about the package, the outer end of said strip portion being adapted to be grasped by the fingers.

3. In a package of gum or other package having 10 an outer wrapper of cellulose acetate, the improvement which comprises a tab projecting from the outer edge of the wrapper, and a double folded flat strip portion in the cellulose acetate extending about the package and to the outer 15 end of said tab.

4. In a package of gum or other package having 20 a sheet of cellulose acetate wrapped thereabout with the longitudinal edges of the sheet overlapping and secured together by adhesive, the improvement which comprises a tab projecting from the outer longitudinal edge of the sheet and a narrow double fold in the sheet extending about the package and through said tab.

5. A structure according to claim 4 in which 25 cuts are provided in the cellulose acetate through the outer longitudinal edge thereof and adjacent the inner ends of the edges of the tab.

6. A structure according to claim 4 in which 30 cuts are provided in the cellulose acetate through the outer longitudinal edge thereof and adjacent opposite edges of the fold.

7. A wrapper of cellulose acetate comprising 35 a sheet having opposed edges thereof extending transversely of the grain of the cellulose acetate and having a narrow folded portion extending across said sheet and through said edges.

8. A structure according to claim 7 in which 40 one of said edges is provided with a projecting tab through which said folded portion extends.

9. A structure according to claim 7 in which 45 one of said edges is provided with a tab through which said folded portion extends and the sheet is further provided with cuts extending through said edge and arranged adjacent the inner ends 50 of the edges of the tab.

10. In a package of gum or other package having 55 an outer wrapper of cellulose acetate, the improvement which comprises a flat fold in the same general direction as the grain of the cellulose acetate, cuts provided in the outer edge of the wrapper spaced a distance from opposite sides of the overlapping portions of said fold, and a tab on said outer edge of the wrapper through 60 which said fold extends with the inner edges of said tab arranged adjacent said cuts in the wrapper.

DOUGLAS M. McBEAN.
